UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE-PLACER.

1,375,732.

Specification of Letters Patent. Patented Apr. 26, 1921.

Application filed July 12, 1918. Serial No. 244,638.

To all whom it may concern:

Be it known that I, EPPA H. RYON, a citizen of the United States, residing at Waltham, in the county of Middlesex and State 5 of Massachusetts, have invented a new and useful Shuttle-Placer, of which the following is a specification.

This invention relates to a device adapted to engage a shuttle which has failed to fully 10 enter its shuttle box, and effective to complete the boxing of the misplaced shuttle. Such a device, while capable of general application, is especially useful on a weft replenishing loom in which correct boxing of 15 the shuttle is essential to proper operation of the replenishing mechanism.

It is the general object of my invention to provide a shuttle placer of an improved and simplified construction, adapted to be 20 supported on a fixed part of the loom, and preferably effective to stop the loom if the shuttle is so far misplaced that it cannot be boxed by the shuttle placer.

In its preferred form, the shuttle placer 25 comprises a shuttle-engaging head movably mounted on a support which is itself also capable of movement, the movements of both head and support being yieldingly resisted. When engaged by a misplaced shuttle, the head is moved upon its support and by such movement forces the shuttle into the shuttle box. If the shuttle is too widely 30 misplaced, the head and support move as a unit and actuate the loom stopping devices.

Important features of my invention relate to the design and disposition of the several parts of the device, whereby the desired movement of the shuttle is accomplished.

My invention further relates to arrangements and combinations of parts herein-after described and more particularly pointed out in the appended claims.

45 A preferred form of my invention is shown in the drawings, in which—

Figure 1 is a plan view of certain portions of a loom with my improved shuttle placer mounted thereon;

50 Fig. 2 is a detail view similar to Fig. 1, partly in section, and showing certain of the parts in a different position;

Fig. 3 is a side elevation of the shuttle

placer, looking in the direction of the arrow 3 in Fig. 1;

Fig. 4 is a sectional plan view taken along the line 4—4 in Fig. 3;

Fig. 5 is a detail sectional view taken along the line 5—5 in Fig. 4, and

Figs. 6, 7 and 8 are diagrammatic views 60 showing the operation of the shuttle placer in relation to differently positioned shuttles.

Referring to Fig. 1, I have indicated a portion of a loom side 10, a breast beam 11, a lay 12, a shuttle 13, and a picker 13, all 65 of the usual construction. The usual filling fork 14 is slidably mounted on the breast beam and operates through a knock-off lever 15 to release the shipper handle 16.

My improved shuttle placer comprises a 70 shuttle-engaging head 17 pivoted at 18 to a support or slide 19 mounted for straight-line movement in a stand 20. A spring 21 (Fig. 3) within the slide forces the same yieldingly rearward to the normal position 75 shown in Figs. 1 and 3. A rod 22 (Fig. 3) is secured within the slide and extends through a bearing in the stand 20. The spring 21 surrounds the rod 22, which acts both as a guide for the slide and as a support for the spring.

The head 17 is grooved at 23 (Fig. 5) on its shuttle-engaging face, and the body portion of said head is slotted to receive a tension spring 24 (Fig. 4) connected between the head 17 and the slide 19. Co-operating stop shoulders 25 and 26 are formed on the head and slide respectively, and the spring 24 tends to move the head to the normal position, in which these shoulders engage each other as shown in Fig. 6.

The shuttle-engaging face of the head 17 is preferably given the irregular outline shown in the drawings with the projecting shoulder 17^a at the extreme outer end thereof. A spring-pressed plunger 27 (Figs. 1 and 2) is slidably mounted in a bearing 28 at one end of the knock-off lever 15. When the slide 19 is moved forward the plunger 27 is engaged thereby, and the knock-off lever is thus moved to release the shipper 16. As the slide moves forward, the plunger 27 eventually slips by the engaging corner of the slide and assumes the position shown in Fig. 2. This release of the knock-off 100 lever before the slide reaches its extreme 105

forward position permits the slide to return to its normal position, sliding easily past the spring plunger without binding.

The operation of my improved shuttle 5 placer is clearly shown in Figs. 6, 7 and 8.

Fig. 6 indicates the relative position of the shuttle placer and the shuttle S when the latter has been properly boxed and therefore requires no assistance from the shuttle 10 placer.

Fig. 7 indicates in dotted lines the position of the shuttle S when it has not fully entered the shuttle box and when in fact it is misplaced to the extreme limit which can 15 be corrected by the shuttle placer shown in the drawings, the point of the shuttle barely entering the groove 23 in the shoulder portion 17^a of the head 17 as the lay and shuttle move forward. It will be seen that this 20 shoulder portion is disposed to the right of the pivot 18, as shown in Fig. 7, and the head 17 therefore tends to swing to the right when engaged by a shuttle in the position shown in Fig. 7. The spring 24 is of less 25 strength than the spring 21, so that such movement to the right may more readily occur. As the head 17 swings to the right, the shuttle is moved thereby to the fully 30 boxed position indicated in full lines in Fig. 7, the point of the shuttle being disposed against the shoulder 17^a during such movement, as appears in the drawing.

If the shuttle is not widely misplaced and engages the head near its right-hand 35 edge, the head acts as a fixed cam to force the shuttle to position without movement on its pivot. A shuttle placer formed in a single piece may thus be used to secure some 40 of the advantages of my invention, but its field of action will be limited to small displacements.

In Fig. 8 I have indicated the operation of the device when the shuttle is widely misplaced. In this case the head 17 and slide 45 19 are moved directly forward as a unit, engaging the plunger 27 and swinging the knock-off lever 15 to release the shipper lever 16 and stop the loom. It will be noted that the forward movement of the slide 19 50 when thus engaged is much greater than the movement of the usual filling fork slide which operates the same knock-off lever, but such greater movement is permitted by the action of the plunger 27 in slipping past the

edge of the slide 19 after a certain move- 55 ment thereof.

It will thus appear that I have provided an exceedingly simple device comprising two movable parts by which a shuttle will be properly boxed unless too widely misplaced, in which event the loom will be 60 stopped.

Having fully described my invention, it will be evident that changes and modifications can be made therein by those skilled in 65 the art without departing from the spirit and scope thereof as set forth in the claims, and I do not wish to be otherwise limited to the details herein disclosed, but what I claim is— 70

1. In a loom, a movable support and a shuttle placer mounted thereon and normally at rest, said shuttle placer receiving an angular shuttle positioning movement by engagement with a slightly misplaced 75 shuttle.

2. In a loom, a shuttle placer normally at rest and receiving a shuttle-positioning movement only by engagement with a misplaced shuttle. 80

3. In a loom, a shuttle placer supported on a fixed part of the loom and normally at rest, said placer being movable directly by a misplaced shuttle when engaged thereby, to correct the position of said shuttle. 85

4. In a loom, a shuttle-engaging head and a support therefor, said head being mounted for movement on said support to box a misplaced shuttle, and for movement with said support to stop the loom when engaged by 90 a widely misplaced shuttle.

5. In a loom, a stand, a slide yieldingly mounted therein and connected to stop the loom, a head pivoted to said slide, a stop on said slide, and a spring normally holding 95 said head against said stop, said head being movable on its pivot when engaged by a slightly misplaced shuttle and having a cam action to box the shuttle by such movement.

6. In a loom, a stand, a slide yieldingly mounted therein and connected to stop the loom, and a shuttle engaging head pivoted to said slide, said loom stopping connection being disengaged before the completion of the forward movement of said slide. 100 105

In testimony whereof I have hereunto affixed my signature.

EPPA H. RYON.
